UNITED STATES PATENT OFFICE.

JEROME J. EDMUNDSON, OF BIRMINGHAM, ALABAMA.

BEVERAGE-CONTAINER.

1,318,547.

Specification of Letters Patent.

Patented Oct. 14, 1919.

Application filed October 12, 1916. Serial No. 125,251.

To all whom it may concern:

Be it known that I, JEROME J. EDMUNDSON, a citizen of the United States, residing at Birmingham, in the county of Jefferson 5 and State of Alabama, have invented certain new and useful Improvements in Beverage-Containers, of which the following is a specification.

This invention relates to beverage containers and more specifically to containers adapted to hold carbonated beverages at a relatively low temperature. The device may be made either small for portable use or relatively large for use in connection with 15 soda fountains.

One of the objects of the present invention is to provide a beverage container having relatively few parts which will be cheap to manufacture and install. A further object is to provide a simple and practical beverage container of the above general type adapted to hold carbonated beverages and maintain the same at a low temperature for a reasonable length of time.

Other objects will be in part obvious from the annexed drawings and in part indicated in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views, of which:—

Figure 1 is a vertical central sectional view showing the complete device;

Fig. 2 is a similar view showing a modification, certain parts being omitted for the sake of clearness;

Fig. 3 is a view similar to Fig. 2 of another modification or holder for form shown in Figs. 1 and 2;

Figs. 4 and 5 are small detail views, and Fig. 6 is a detailed sectional view of another modification.

Referring now to the drawings in detail

and more particularly to Fig. 1, 10 denotes a single wall bottle or jar adapted to hold the beverage to be dispensed. This bottle may be bought and sold separately and used with 60 the holder or container hereinafter described for the purpose of carbonating the beverage and maintaining the same cool. This bottle 10 is preferably of single thickness provided with a reinforced neck 11 having 65 a stopper 12 with one or more openings therein, through one of which passes a tube 13 leading to a dispensing cock, not shown, for this will vary according to the use to which the device is put. For example in 70 soda fountains it would probably lead to a tap cock some distance away, while if the device is of a small portable variety the tap cock will be placed at the intermediate end thereof. A second pipe 14 is adapted 75 to be connected with a suitable source of carbon dioxide gas for the purpose of carbonating the beverage and also for filling the space between the bottle 10 and its outer container 15 with gas. The pipes 13 and 80 14 pass through a closure 16 in the upper part 17 of the outer casing or jacket and are then forced through the cork or stopper 12 to the interior of the bottle 10. The pipe 13 preferably extends down substantially to 85 the bottom of the bottle, as shown, and the beverage is forced out therethrough by reason of the gas pressure. The pipe 13 is also provided with a small stop cock 18 for maintaining the pressure within the 90 bottle, and the pipe 14 is provided with a check valve 20 to prevent back flow of gas. A small opening 21 is provided in the pipe 14 to permit the gas to flow into the space between the bottle 10 and its casing 15, it 95 being a well recognized fact that carbon dioxide gas is a relatively low conductor of heat, and it thereby provides an insulating means between the bottle and its casing, thus aiding in keeping the beverage at a relatively 100 low temperature for a comparatively long time.

The casing 15 is provided with numerous supporting pads 22 at various places about its interior, adapted to cushion the bottle 105 against jarring, and also keep the bottle in spaced position with respect to the casing. The parts 15 and 17 of the casing are connected near their top and provided with a gasket 23. A clamping ring 24 of wedge-shaped cross section passes around the parts at this point and is preferably provided with

any desired form of tightening means 25, see Fig. 4, whereby the parts may be firmly clamped and held in position. Other forms of tightening and holding means may be substituted, although it is believed that the form herein shown and described will prevent certain advantages and ease of manipulation.

One method of using and operating a device of this character is substantially as follows:

The cover 17 of the casing is removed and a bottle 10 containing the beverage to be dispensed placed therein, after which the stoppers containing the pipes 13 and 14, are put in place, together with the cover 17, and the gasket ring 23 tightened to airtight condition.

The pipe 14 is then connected with a suitable source of carbon dioxide whereby the liquid or beverage will be carbonated, and the space between the bottle and the casing 12 will also be filled with a fluid having a low heat conductivity which also equalizes the pressure on both sides of the bottle, thus preventing breakage thereof. The beverage may then be drawn off through the pipe 13 after the stop cock 18 has been opened.

Fig. 2 shows a modification of substantially the same construction as that above described, except that the casing 26 is preferably of double wall construction and is provided with a double wall cover 28, both of which are provided with valve members 27 whereby the pressure between the double walls may be varied as desired. The bottle 10 is supported by cushioning means similar to the blocks 22 as shown in Fig. 1 and is connected with a suitable source of carbonating fluid and provided with a dispensing tube 13, as above explained. At this point, it may be noted that the bottle 10 may be filled through this dispensing tube, if so desired. The bottles in both cases are preferably made of glass, although this is not essential and the outer casings may be made of glass, metal or fiber, as desired.

It will be seen that this modification presents a device having greater insulating capacity than that shown in Fig. 1.

Fig. 3 is substantially the same construction as Fig. 2 yet a different form of fastening means as shown in Fig. 5 is provided whereby the cover 30 is secured in place. This cover is preferably provided with a separate downwardly extending flange member 31 having one or more holes 32 adapted to receive projecting lugs 33 about the top or the lower part of the casing. This flange or tightening band is provided with projecting ears through which a bolt may be passed substantially as shown in Fig. 4 for tightening the band and drawing the parts of the casing in tight position.

This modification will be found desirable

where relatively high pressure is used between the double walls. If desired, the air could be exhausted from this double space and a medium pressure maintained between the inner wall of the casing and the bottle. It will be noted that the spacers 34 are preferably used between the inner and outer walls of the casing, thereby permitting the use of a relatively large bottle closely fitting the interior of the casing or even the device shown in Figs. 1 and 2.

In Fig. 6, there is shown a further slight modification of the closure means at the top of the receptacle. The bottle 10 and the casing 15 are substantially the same as shown in Fig. 1. A packing and insulating material 35 is positioned adjacent the inner surfaces and is provided with a passage or duct 36 leading to the interior of the casing. The dispensing pipe 13 passes through a tight plug 37 mounted in the insulating material 35 forming a closure for the bottle 10 and has closely fitting thereon a threaded member 38 adapted to engage threads in the upper part of the member 37. When this part is screwed into place, it tightly sits upon the bottom of the threaded recess of the member 37, thus making a tight connection. A small pipe 40 leads through this member 38 and terminates adjacent an indenture 41 in the dispensing pipe 13 which loosely passes through the neck of the bottle and thereby communicates with the interior of the device. This construction permits the carbonating fluid to pass in through the pipe 40 past the indenture 41 to the interior of the bottle 10. A portion of this gas may also pass through the duct 36 into the interior of the casing or that space between the bottle and the casing, thereby to increase the insulation of the device.

It is, of course, to be understood that a different form of member 38 may be used, if desired, such, for example, as a spigot member as commonly used in connection with beer kegs. The method of operating a device of this character is substantially the same as that above described in connection with Fig. 1 and a further statement thereof is believed to be unnecessary.

From the above, it will be clear that the present invention provides a simple, practical and inexpensive beverage container, and accomplishes, among others, all of the objects and advantages herein set forth.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended within the

meaning and range of equivalency of the following claims.

I claim:

1. In a device of the character described, in combination, a bottle, a casing therefor and spaced therefrom provided with a removable cover whereby the bottle may be withdrawn from said casing, said cover being provided with a threaded opening, a threaded closure in said opening, a dispensing tube passing through said threaded closure, and a passage way through said closure adapted to convey a carbonating fluid to the interior of the bottle and receptacle.
2. In a device of the character described, in combination, a bottle, a casing having a removable cover therefor, said cover having an opening, a stopper fitting in said opening, a dispensing tube passing through said stopper and loosely passing through the neck of the bottle, a second tube passing through the stopper for conveying a carbonating gas to the interior of the bottle, an insulating material positioned between the neck of the bottle and the interior of the casing having a passageway communicating with said first mentioned passageway whereby the carbonating gas may also enter the space between the casing and the bottle.
3. In a device of the character described, in combination, a bottle, a casing therefor and spaced therefrom provided with a removable cover whereby the bottle may be withdrawn from said casing, said cover being provided with a threaded opening, a dispensing tube having a fastening member engaging said threaded opening, a passage way through said last mentioned member adapted to convey a carbonating fluid to the interior of the bottle, and an insulating spacing member between the bottle and the casing, said spacing member constituting a closure for the bottle, and being provided with a passage way communicating with said first-named passage way at one end,

and with the space between the bottle and the casing at the other end.

4. In a device of the character described, in combination, a bottle, a casing therefor and spaced therefrom provided with a removable cover whereby the bottle may be withdrawn from the casing, said cover having an opening, a threaded plug disposed within the opening, a dispensing tube arranged to pass through the plug and into the interior of the bottle, a holding member for said dispensing tube having threads arranged to engage the threaded plug, an inlet tube carried by said holding member, and a passage way through said plug for establishing communication between said inlet tube and the space between the bottle and the casing.

5. In a device of the character described, in combination, a bottle, a casing therefor and spaced therefrom provided with a removable cover whereby the bottle may be withdrawn from the casing, said cover having an opening, a threaded plug disposed within the opening, a dispensing tube arranged to pass through the plug and into the interior of the bottle, a holding member for said dispensing tube having threads arranged to engage the threaded plug, an inlet tube carried by said holding member, a passage way through said plug for establishing communication between said inlet tube and the space between the bottle and the casing, an insulating spacing member disposed between the bottle and the casing and constituting a stopper for the bottle, and having a passage way communicating with the passage way in the plug.

In testimony whereof I affix my signature in presence of two witnesses.

JEROME J. EDMUNDSON.
